Primary Examiner — Holly Baynam(74) *Attorney, Agent, or Firm* — David A. Burge(57) **CLAIM**

I claim the ornamental design for a cable support insert, as shown and described.

DESCRIPTION

Reference is made to Design U.S. Appl. No. 29/395,835 filed Apr. 6, 2012 which depicts a mounting bracket having a tubular upstanding stem into which a depending tubular stem of the cable support insert embodying the present design may telescopically extend while a cable can be attached to the annular ring(s) located on a side of the upstanding stem.

FIG. 1 is a perspective view showing front, top and right side features of a first embodiment of my design which has an elongate tubular stem that is of indefinite length, with an annular collar on the right side thereof near an upper end of the tubular stem;

FIG. 2 is a front elevation view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view of a second embodiment of my design;

FIG. 8 is a right side elevation view thereof; and,

FIG. 9 is a left side elevation view thereof.

Top and bottom plan views of the second embodiment are omitted inasmuch as they would be identical to FIGS. 3 and 4 hereof.

The broken lines showing a nut and bolt are for the purposes of illustrating environment and form no part of the claimed design.

1 Claim, 4 Drawing Sheets---
